UNITED STATES PATENT OFFICE

ALBERT S. HOWELL, OF CHICAGO, ILLINOIS, ASSIGNOR TO THE BELL & HOWELL COMPANY, OF CHICAGO, ILLINOIS, A CORPORATION OF ILLINOIS

PICTURE-PROJECTING MACHINE

Application filed August 17, 1928. Serial No. 300,229.

My invention relates to motion picture projecting machines although not limited to this use alone.

The general objects of my invention relate in the provision of a simple, effective and convenient means whereby a picture projecting machine may be adjusted to project pictures to a desired position, and which is particularly adapted to a projecting machine which is foldable into compact form for storage and transportation.

With these objects in view my invention consists in certain features of novelty in the construction, combination and arrangement of parts by which the said objects and certain other objects, hereinafter appearing, are effected, all as fully described with reference to the accompanying drawings and more particularly pointed out in the appended claims.

20 In the said drawings—

Figure 1 is a side elevation of a motion picture projecting machine embodying my invention and extended or unfolded and ready for use;

25 Figure 2 is a similar view with the machine folded for storage and transportation and with parts broken away and in section;

Figure 3 is an enlarged similar side elevation of a portion of the machine;

30 Figure 4 is a section on the line 4—4 of Figure 2; and

Figure 5 is an enlarged perspective view of a portion of the mechanism.

Like characters of reference indicate like parts in the several views.

35 Referring to the drawings, the motion picture projecting machine illustrated is similar to that described and claimed in U. S. Letters Patent No. 1,587,955, granted June 8, 1926, for improvement in motion picture projecting machine and the like, and requires no detailed description for the present purposes.

The machine includes a base or supporting member comprising a hollow standard 1 and a laterally extending base 2 at the bottom of the standard, and a composite frame 3, carrying the mechanism and projecting devices of the machine, is pivotally supported on the upper end of the standard on an axis transverse thereto by means of a headed pivot

stud screw 4 passing through a bore through the upper end of the standard 1 and screw-threaded into a pivot extension 5 on the frame 3. See Figures 1 to 4 inclusive.

As so supported on the base the frame 3 is pivotally movable into and out of a folded position adjacent the base. Figure 2 shows the frame 3 in its folded position adjacent the base and Figure 1 shows this frame out of this position and in an extended relation with respect to the base ready for the operation of the machine.

45 A crank stud 6 is fixed on the extension 5 of the frame 3 adjacent the pivotal axis of this frame and projects into the enclosure of the standard 1 through an arcuate slot 7 in the standard and arranged on an axis coincident with that of the pivot stud 4, this arcuate slot 7 permitting movement of the crank stud 6 with the frame 3 in its pivotal movement aforementioned. See Figures 2 and 4.

50 An apertured plate 8 is secured within the standard 1 adjacent the lower end thereof, and a rod 9, also within the standard, is slidably engaged in the aperture of this plate and extending upwardly therefrom engages upwardly against the crank stud 6 with its upper end which is V-shaped, as designated at 11 in Figure 2, to maintain the rod engaged with this stud.

55 A helical compression spring 12 encircles the rod 9 and abuts downwardly on the plate 8, and the upper end of this spring abuts a slotted washer 13 engaged in a circumferential groove 14 on the rod, see Figure 5, to form a shoulder on the rod.

60 As so arranged the spring urges the rod 9 upwardly against the stud 6 to yieldably urge the frame 3 in a direction away from its folded position when the frame has an extended relation with the base, as shown in Figure 1.

65 However, the stud 6 is so disposed that it is slightly passed or substantially at dead center when the frame 3 is in its folded position adjacent the base, as shown in Figure 2, so that the frame 3 will remain in this position until moved out of the same.

The standard 1 is provided at its upper end with an ear 15 through which is screw-

threaded a manually operated adjusting stop screw 16, see Figures 1, 2 and 3, which engages the frame 3 to adjustably position the frame 3 in its extended relation with respect to the base against the influence of the spring 12, the spring holding the frame 3 against the screw 16 so that the frame 3 may be adjusted in either direction by manipulating this screw.

10 Thus it will be observed that a convenient means is provided for the adjustment of the frame 3 to project at desired points vertically, the horizontal adjustment of the machine for this purpose being effected by bodily turning the machine.

15 It will also be observed that the construction permits of the convenient folding of the machine, and that the spring 12 and related parts are desirably concealed within the 20 standard.

25 While I have described and shown the preferred embodiment of my invention I do not wish to be limited to the precise details of construction as changes may readily be made without departing from the spirit of my invention, but having thus described my invention, I claim as new and desire to secure by Letters Patent the following:

30 1. In a picture projecting machine the combination with a supporting member provided with a hollow standard and a supported member pivotally mounted on said standard on an axis transverse thereto, of spring means within said standard and yieldably urging 35 said supported member in one direction with respect to said supporting member, and manually controlled adjusting means for operating said supported member in the opposite direction with respect to said supporting member.

40 2. In a picture projecting machine the combination with a supporting member and a supported member pivotally mounted thereon for movement into and out of a folded 45 position adjacent said supporting member, of a crank on one of said members, spring means operating on said crank for yieldably urging said supported member in a direction away from said position when said supported member has an extended relation with 50 said supporting member, said crank being disposed to prevent movement of said supported member out of said position by said spring means; and means for adjustably positioning said supported member in said extended relation against the influence of said spring.

55 3. In a picture projecting machine the combination with a supporting member and 60 a supported member pivotally mounted thereon for movement into and out of a folded position adjacent said supporting member, of a crank on one of said members, spring means operating on said crank and 65 acting on the other of said members for yield-

ably urging said supported member in a direction away from said position when said supported member has an extended relation with said supporting member, said crank being disposed substantially at dead center 70 when said supported member is in said position, and a manually operated stop screw screwthreaded on one of said members for adjustably positioning said supported member in said extended relation against the influence of said spring.

4. In a picture projecting machine the combination with a supporting member comprising a hollow standard and a laterally extending base at the bottom of the standard, 80 and a supported member pivotally mounted on the upper end of the standard on an axis transverse thereto for movement into and out of a folded position adjacent said supporting member, of a crank on said supported member adjacent its pivotal axis and projecting into the enclosure of said standard, an apertured formation within the standard adjacent its lower end and fixed therewith, a rod within said standard and 85 slidably engaged in the aperture of said formation and engaging said crank, a helical compression spring encircling said rod and abutting downwardly on said formation, shoulder means on said rod above said spring 90 and against which said spring acts to urge the rod upwardly against said crank to yieldably urge said supported member in a direction away from said position when said supported member has an extended relation with 95 said supporting member, said crank being disposed substantially at dead center when said supported member is in said position, and a manually operated stop screw screwthreaded on one of said members for adjust- 100 ably positioning said supported member in said extended relation against the influence of said spring.

105 In witness whereof I hereunto affix my signature this 13th day of August, 1928.

110 ALBERT S. HOWELL.
